Lloyd W. Phelps, 1020 Portland Ave., Gladstone, Oreg.

Filed Jan. 7, 1963, Ser. No. 73,055

Term of patent 14 years

(Cl. D42—7)

FIG. 1.

FIG. 2.

FIG. 3.

FIG. 4.

FIG. 1 is a front elevational view of a clock showing my new design;

FIG. 2 is a side elevational view thereof;

FIG. 3 is the top plan view thereof; and

FIG. 4 is a section view taken on the line 4—4 in FIG. 1.

The rear of the clock, not shown, is substantially plain and unornamented; and the side not shown is substantially identical to the side shown in FIG. 2.

The essential features of my design reside in the portions shown in full lines in the drawings.

I claim:

The ornamental design for a clock, as shown and described.
